US0D1006539S

(12) **United States Design Patent** (10) **Patent No.:** **US D1,006,539 S**
(45) **Date of Patent:** **** Dec. 5, 2023**

(54) **VERTICAL COOKER GRATE**

(71) Applicant: **Pit Barrel Cooker Co, LLC**,
Louisville, KY (US)
(72) Inventor: **Noah E Glanville**, Murphy's, CA (US)
(**) Term: **15 Years**

(21) Appl. No.: **29/794,134**

(22) Filed: **Jun. 10, 2021**

(51) **LOC (14) Cl.** **07-02**
(52) **U.S. Cl.**

USPC **D7/408; D7/409**

(57) **CLAIM**

The ornamental designs for a vertical cooker grate, as shown and described.

DESCRIPTION

FIG. 1 is a perspective view of a vertical cooker grate;

FIG. 2 is a top view of FIG. 1;

FIG. 3 is a bottom view of FIG. 1;

FIG. 4 is a side view of FIG. 1;

FIG. 5 is an opposite side view of FIG. 4;

FIG. 6 is a front view of FIG. 1; and,

FIG. 7 is a back view of FIG. 1.

The broken lines in FIGS. 1–7 show portions of the article that form no part of the claimed design.

1 Claim, 2 Drawing Sheets
